[57] CLAIM

The ornamental design for a drinking water dispenser or similar article, as shown and described.

DESCRIPTION

FIG. 1 is a top, right front perspective view of a drinking water dispenser or similar article, showing my new design;

FIG. 2 is a front elevational view thereof;

FIG. 3 is a rear elevational view thereof;

FIG. 4 is a left side elevational view thereof;

FIG. 5 is a right side elevational view thereof; and

FIG. 6 is a top plan view thereof.
The bottom of the drinking water dispenser or similar article is plain.
